UNITED STATES PATENT OFFICE.

EDWARD P. FLYNN, OF ROCHESTER, NEW YORK, ASSIGNEE TO EASTMAN KODAK COMPANY, OF ROCHESTER, NEW YORK, A CORPORATION OF NEW YORK.

ENVELOPE FOR PHOTOGRAPHIC LIGHT-SENSITIVE MATERIAL.

Application filed April 3, 1924. Serial No. 704,043.

My invention relates to an improved form of envelope designed particularly for use with photographic light sensitive material such as is commonly known as "printing paper." One object is to provide an envelope from which the sensitized material can be easily removed in a dark room without danger of bending or abrading the paper; another object is to provide an envelope which is suitable for repacking unused sheets of paper; another object is to provide a handle extending beyond the limits of the envelope to facilitate handling the sensitized products without bending or abrading; and other objects will appear from the following specification, the novel features being pointed out in the claim at the end thereof.

The usual package of light sensitive printing paper consists of a number of sheets of the sensitive paper wrapped in black paper or placed in an inner envelope, and this is in turn placed in the covering or outer envelope. The inner package must be made light tight, and is preferably arranged so that the original package may be used as a container for the light sensitive materials after some of the sheets have been removed for use.

As is well known, paper or other supports covered with a photographic light sensitive emulsion are susceptible to abrasion or friction markings. Some paper surfaces are more susceptible than others, the glossy or enameled surfaces generally being most difficult to keep free from these objectional markings. Such marks, which develop up in irregular dark lines may be caused in a variety of ways, among which are direct pressure, such as may be caused by pulling out the paper while holding it through the walls of an envelope; and sharp bending, such as may be caused by pressing the edges of an envelope together in an attempt to open the end of a package widely to permit the inner package to be removed. Binding is also apt to crack some of the more brittle emulsions such as are used on certain types of printing papers. It is desirable to eliminate the sources of trouble as far as possible, and this invention relates to a means for overcoming such difficulties as may result from opening the original package, and such subsequent insertions and removals from the envelope as may occur.

Ordinarily the inner wrapping or envelope for the sensitized paper fits closely into the outer envelope, and if the latter envelope be grasped by one hand while endeavoring to withdraw the inner package with the other hand, the paper can be and frequently is bent and considerable pressure may be applied through the walls of the package.

It is therefore desirable to provide a package which can be loaded and unloaded with sensitized material with a minimum amount of friction, and I have provided an envelope to be hereinafter fully described, in which a handle is provided beyond the walls of the outer envelope for holding the envelope without applying any pressure to the contents thereof while the inner package may be moved relative to the envelope. I have provided the handle directly opposite the open end of the envelope in a position in which it can be used to hold the outer envelope against the force being applied to the inner package in removing it from the envelope. This handle can also be used to hold the envelope while the inner package is being inserted into the envelope. Being located on the line of force used in either loading or unloading, friction is reduced to a minimum and the entire package can be handled without danger of abrasion.

Coming now to the drawings where like reference characters denote like parts throughout,

Fig. 1 is a perspective view of an envelope constructed in accordance with and illustrating one embodiment of my invention;

Fig. 2 is a plan view of a blank for making another embodiment of my invention;

Fig. 3 is a plan view of the envelope made from the blank shown in Fig. 2; and

Fig. 4 is an enlarged section on line 4-4 of Fig. 1.

In Fig. 1 the envelope E is formed of a sheet of paper 1, having the sides 2 of the sheet folded at 3 and joined at 4. A flap 5 is provided at one end through which the inner package P may be inserted or removed. This package may be an envelope or a sheet of wrapping paper enclosing the sensitized paper sheets S. At the opposite end from flap 5 there is a second flap 6 preferably fastened against the sides 2 by pasting.

For holding the outer envelope E for the

removal or insertion of the inner package P I provide a handle which may be in the form of a flap 10 as shown in Fig. 1 having sides 11 which may extend from a fold 12. 5 One portion 13 of each side is pasted against the central portion of the end 14 of envelope E and another portion 15 of each side is pasted against the opposite portion of the flap to form a handle H of a double thickness of material. The location of the handle H is important, being positioned upon the line of force applied to package P when it is being inserted into or removed from envelope E. By holding the handle H the 10 edge 20 of the inner package P can be grasped and a straight pull will withdraw the inner package without any tendency for this package to bind at the edges or to be otherwise frictionally retained in envelope 15 E. The tab or handle H can be readily found in a dark room, where such a package is always handled, and being made of flexible material may be folded against the envelope E for shipping. 20 In Figs. 2 and 3 I have shown another embodiment of my invention wherein a sheet 50 is cut with a flap 51 at one end and a second flap 52 at the other end. Flap 52 consists of three parts, 53, 54, and 55, the 25 first and last being identical in size and shape. Flap 54, however, extends beyond the other flaps, and may broaden out into an end 56. Binding the blank shown in Fig. 2 along the dashed lines b and suitably fastening the edges 57, together as well as flaps 53, 54 and 55 produces the envelope e shown 30 in Fig. 3.

As end 56 is fastened over the edges 58 of flaps 53 and 55 it forms an additional retaining means for these flaps, and being 35 pasted upon itself at 59 and the envelope e

at 60, it forms an integral handle h of a double thickness of material.

As in the first embodiment of my invention the handle h is positioned in the center 45 of the end 61 of the envelope directly opposite the flap 51 past which the inner package P is inserted or removed.

In both embodiments of my invention the outer envelope can be, and generally is used 50 for packing the sensitized sheets of paper which may not be used when the package is open.

Having thus described my invention, what I claim as new and desire to secure by 55 Letters Patent is:

In an envelope having an open end and adapted to contain an inner package of photographically light sensitive material capable of being marred by pressure, a flap 60 for closing the open end, said flap being adapted to be opened for the insertion or removal of the inner package by a force applied transverse to the flap and to the open end of the envelope, a closed end at the end 65 of the envelope opposite the open end provided with a flap extending beyond the walls of the envelope forming a handle for holding the envelope without squeezing the 70 inner package through the walls of the envelope as the inner package is being moved through the open end, the flap being positioned on the envelope on a line coincident with the line of force applied to insert or remove the inner package from the envelope, whereby the sensitized material may be moved relative to the envelope with a 75 minimum of friction.

Signed at Rochester, New York this 27th day of March 1924.

EDWARD P. FLYNN.
